CLAIM

The ornamental design for a replacement head for an oral care implement, as shown and described.

DESCRIPTION

FIG. 1 is a front perspective view of a replacement head for an oral care implement according to a first embodiment of the new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of a replacement head for an oral care implement according to a second embodiment of the new design;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines in the drawings formed by linear segments of equal length illustrate portions of the article that form no part of the claimed design.

1 Claim, 8 Drawing Sheets
